CLAIM

The ornamental design for a hot-beverage maker, as shown and described.

DESCRIPTION

FIG. 1 is a front view of a hot-beverage maker showing my new design in a configuration for storage;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a perspective view thereof;

FIG. 8 is a perspective view thereof with the cup removed for ease of illustration;

FIG. 9 is a top plan view thereof;

FIG. 10 is a top view of the cup element as omitted from FIGS. 8 and 9;

FIG. 11 is an exploded perspective view of FIG. 8; the surfaces of the exploded elements not shown are plain and unornamented;

FIG. 12 is a front view of the hot-beverage maker of FIG. 1 with various elements in an in use position; and,

FIG. 13 is a perspective view thereof.
